TELEPHONE BOOTH

Leslie A. Hannula, Waukegan, Martin B. Schaffer, Park Forest, and Edward S. Ertl, Island Lake, Ill., assignors to Acoustics Development Corporation, Park Ridge, Ill., a corporation of Illinois

Filed Dec. 5, 1962, Ser. No. 72,730

Term of patent 14 years

(Cl. D13—1)

FIGURE 1 is a front elevational view of a telephone booth showing our new design, with the telephone mounting plate shown in broken lines for illustrative purposes only, and the word "telephone" shown in broken lines for illustrative purposes only,

FIGURE 2 is a rear elevational view of a telephone booth showing our new design, with the word "telephone" shown in broken lines for illustrative purposes only,

FIGURE 3 is a side view of a telephone booth showing our new design, with the word "telephone" shown in broken lines for illustrative purposes only,

FIGURE 4 is a top plan view of a telephone booth showing our new design, and

FIGURE 5 is a bottom plan view of a telephone booth showing our new design.

The dots shown in the interior of the booth in FIGURES 1 and 5 indicating acoustical material have been

only partially shown for convenience of illustration only, it being understood that the dotted acoustical material continues throughout the adjacent plain areas shown to complete the interior pattern.

The side of the booth not shown is identical with the side shown in FIGURE 3.

We claim:

The ornamental design for a telephone booth, as shown and described.
